UNITED STATES PATENT OFFICE.

JAMES S. WATSON, OF NEWTON, MASSACHUSETTS.

IMPROVED WRITING-DESK.

Specification forming part of Letters Patent No. 43,876, dated August 16, 1864.

To all whom it may concern:

Be it known that I, JAMES S. WATSON, of Newton, in the county of Middlesex and State of Massachusetts, have invented a new and useful Improvement in Writing-Desks; and I do hereby declare the same to be fully described in the following specification and represented in the accompanying drawings, of which—

Figure 1 is a top view, and Fig. 2 a transverse section, of one of my improved desks as closed. Fig. 3 is a top view, and Fig. 4 a transverse section, of it as open. Fig. 5 is an inner side view of one of its ends and the groove thereof, in which the flexile cover of the inkstand and pen-case slides during the movement of the draw either out or in.

The nature of my invention consists in the combination and arrangement of a flexile cover for the inkstand and pen-case, with the drawer, in such manner as to be caused to move and uncover the inkstand and pen case by and during the pulling out of the drawer and to move back and cover over the said inkstand and pen case by and during the return movement or closing of the drawer; and my invention further consists in an arrangement of either or both the slanting covers of the desk, whereby, when such and the drawer are closed, the flexile cover of the inkstand and pen-case shall close down upon or over either or both of such slanting covers and hold it or them down, or prevent the same from being raised relatively to the remainder of the desk.

In the drawings, A denotes the body of the desk, which is provided with a drawer, B, and an inkstand and pen-case, C, the latter and a covered space, D, being arranged in manner as shown in the drawings. The inkstand and pen-case are for the reception and holding of an inkstand, pens, a sand-box, and various other matters, and may be made like those in ordinary use in other desks. The space D is that which is usually situated directly underneath the inclined tablet E, on which the sheet of paper is generally laid while being written upon. In this desk the tablet is made in two parts, E E', and they are hinged to the body A at *a* and *b*. They constitute a double cover for the space D, and when the part E' is turned down, as shown in Figs 3 and 4, it forms a continuation of the part E, or makes

with it an inclined plane for supporting a sheet of paper while being written on.

A circular segmental groove, *c*, opening into a straight groove, *c'*, is made on the inner face of each end of the body A, the top of the straight groove *c'* being on or about on a level with that of the drawer B. Within the groove *c c'* of each end of the body A a flexile cover, F, is inserted. When the desk is made as shown in the drawings and the flexile cover is closed the upper end of this flexile cover will rest on the top of the part E', the lower end of the said flexile cover being attached to the drawer. This flexile cover consists of a series of bars or strips of wood, *ddd*, &c., laid parallel and close to one another and hinged together or cemented to a sheet of leather or cloth, *e*, each of such bars or strips being semi-circular, or thereabouts, in transverse section and cemented and arranged on the sheet of cloth in manner as shown in the drawings. The flexile cover when closed covers or encloses the inkstand and pen-case C.

On pulling open the drawer the flexile cover will be drawn into the straight grooves *c'* and more or less out of the curved grooves *c*, and will uncover the part C. While closing the drawer a reversed motion of the flexile cover will take place.

By my construction of a writing desk it will be seen that one lock applied to the drawer and locked will suffice to prevent the drawer, the flexile cover, and the covers E E' from being opened.

I claim as my invention—

1. The combination and arrangement of the flexile cover for the inkstand and pen-case with the drawer, so as to be operated thereby and with respect to the inkstand and pen-case of the writing-desk, substantially as hereinbefore specified.

2. The arrangement of either or both the slanting covers E E' of the desk with the flexile cover, in manner substantially as described—that is, so that the said flexile cover when closed shall rest upon and close down such slanting cover or covers, as specified.

J. S. WATSON.
